UNITED STATES PATENT OFFICE

2,145,741

RECLOSING CIRCUIT BREAKER

Wilhelm Stäblein, Berlin-Hermsdorf, Raoul Willheim, Berlin-Oberschöneweide, and Werner Uebermuth, Bielefeld, Germany, assignors to General Electric Company, a corporation of New York

Application October 14, 1937, Serial No. 169,060
In Germany October 29, 1936

6 Claims. (Cl. 200—89)

This invention relates to high speed reclosing circuit breakers, more particularly to a power circuit breaker or disconnecting switch which is to effect a brief interruption of one or more phases of a high voltage power circuit and has for its principal object the provision of an improved reclosing breaker mechanism that is simple and compact in design and efficient and very fast in operation.

10 In an application of high speed reclosing circuit breakers to remote control systems, for example, a momentary voltage or circuit drop in the power network for executing switching signals or commands is caused by quickly opening and closing a breaker in one or more phases of the power circuit at the central station. The signals which can relate to the switching on and off of street lighting, night demand apparatus, etc. may be periodic and coordinated as desired. Where the 15 signals are used in power current networks, they may be picked up by a plurality of receivers distributed in the network. In this connection, it has been proposed that a single phase of the power network be interrupted according to a code 20 for a very short duration, such as one cycle of the alternating current and that the interval between two or more such impulses be utilized for the signal characteristic.

The circuit breaker can be of any suitable type 30 that is capable of interrupting a power circuit within one to three or four alternating current cycles. A greater duration may cause synchronous machines to fall out of step, etc.

In another application of the invention, the 35 breaker may be readily adapted for automatic reclosing in case of a momentary fault in the power circuit. In such cases, it is highly desirable that continuity of service be maintained where the fault such as a lightning surge is of 40 brief duration.

Our invention will be more fully set forth in the following description referring to the accompanying drawing, and the features of novelty which characterize our invention will be pointed 45 out with particularity in the claims annexed to and forming a part of this specification.

Referring to the drawing, Fig. 1 is a partly diagrammatic perspective view of a reclosing circuit breaker mechanism embodying our invention in 50 the closed circuit position, and Fig. 2 is a similar view of part of the mechanism in the open circuit position immediately prior to reclosure.

The circuit breaker proper, which as previously stated can be of any suitable type is generally 55 indicated at 1 and comprises a fixed contact 2

coacting with relatively movable contact structure such as the rod contact 3. The circuit breaker controls a power circuit indicated at 4. For the purpose of effecting circuit opening movement of the rod contact 3, a suitable operating device such as a solenoid 5 is operatively connected to the breaker through a crank 6 and shaft 7 in a manner presently set forth. The solenoid 5 can be suitably energized from a control source 8 by a switch diagrammatically indicated at 9. The switch 9 of course can be remotely controlled in a conventional manner such as by relays and the like. The solenoid 5 is also provided with a resetting spring 10 which is shown as directly connected through a crank 11 15 to the shaft 7.

The movable contact 3 is operatively connected to the shaft 7 through a crank 12 and a hollow shaft 13 which is concentrically mounted with respect to the shaft 7 and is adapted to be locked thereto by means of a locking or latching device generally indicated at 14. Accordingly, when shafts 7 and 13 are locked together, energization of the solenoid 5 is effective to rotate both shafts in a clockwise direction, as viewed, so as to cause 25 separation of the breaker contacts 2 and 3. When unlocked, the shaft 13 is freely rotatable independent of the shaft 7.

During this circuit opening movement an energy storing device, such as a spring 15 connected 30 to the shaft 13 through a crank 16, is charged so that it tends to cause reclosure of the contact 3. By means of the locking device 14 the connection between the shafts 7 and 13 can be broken after a predetermined circuit-opening movement so 35 that the spring 15 is effective instantaneously to cause reclosure of the contact 3 independently of the operating solenoid 5.

Referring more particularly to the locking device 14, the shaft 13 which is suitably journaled 40 at 17 has secured thereto a locking disk 18 having a detent 19. The shaft 7 in turn has secured thereto a latch carrying member 20 on which a latching member 21 is pivotally mounted at 22. The latch 21 is biased toward its latching position by a spring 23 and is provided with a vertical portion 24 for coacting with an adjustable stop member 25 and an offset portion 26 for coacting with the detent 19.

In the closed circuit position shown by Fig. 1 50 the latch 21 through the offset portion 26 and detent 19 forms a releasable connection between the shafts 7 and 13. In this position, operation of the solenoid 5 rotates both shafts in unison. When, however, the contact 3 reaches a prede- 55

terminated position the latch portion 24 engages the adjustable stop 25 so as to cause rotation of the latch in a counterclockwise direction as viewed in Fig. 2 and release of the detent 19. The unlocking or releasing operation at this instant is shown by Fig. 2. The stressed spring 15 is instantly effective after the releasing operation to rotate the shaft 13 counterclockwise at high speed to cause reclosure of the rod contact 3 independently of the solenoid 5.

Immediately upon reclosure of the breaker and deenergization of the solenoid the main operating shaft 7 is reset by the spring 10 so that the latch carrying member 20 assumes its original position shown in Fig. 1 wherein the latch 21 is again reset with respect to detent 19 and in readiness for another circuit opening operation.

The latch 21 can of course be controlled by a conventional over-current relay instead of by the fixed stop member 25 if desired, so that the releasable connection is not necessarily broken with each circuit-opening operation of the breaker.

It should be understood that our invention is not limited to specific details of construction and arrangement thereof herein illustrated, and that changes and modifications may occur to one skilled in the art without departing from the spirit of our invention.

What we claim as new and desire to secure by Letters Patent of the United States is:

1. A high speed reclosing circuit breaker comprising movable contact structure, means for biasing said contact structure to closed circuit position, means for operating said contact structure to open circuit position against said biasing means, and means for causing high speed reclosure of said contact structure independently of the position of said operating means in response to predetermined opening movement thereof.

2. A high speed reclosing circuit breaker comprising movable contact structure, a power storing device, means for charging said device and causing circuit opening movement of said contact structure, and means operatively related to said device for causing automatic reclosure of said contact structure independently of continued operation of said first-named means after predetermined opening movement thereof.

3. A high speed reclosing circuit breaker comprising movable contact structure, means for biasing said contact structure to closed circuit position, means for operating said contact structure to open circuit position against said biasing means, and releasable means interconnecting said biasing means and said operating means for causing high speed reclosing of said contact structure independently of said operating means.

4. A high speed reclosing circuit breaker comprising movable contact structure, means for biasing said contact structure to closed circuit position, means for operating said contact structure to open circuit position against said biasing means, and latching means for releasing said operating means with respect to said biasing means in response to predetermined circuit opening movement for causing high speed circuit reclosure.

5. A high speed reclosing circuit breaker comprising movable contact structure, a spring for biasing said structure to closed circuit position, operating means for moving said structure to open circuit position against the bias of said spring, a latch for interconnecting said spring and operating means, and means for actuating said latch in response to predetermined circuit opening movement whereby said spring is effective to reclose said contact structure independently of said operating means.

6. A high speed reclosing circuit breaker comprising movable contact structure, a spring normally biasing said structure to closed circuit position, operating means for moving said structure to open circuit position, a releasable connection between said spring and operating means including a latch whereby said contact structure and operating means are interconnected during the initial circuit opening movement, and means cooperating with said latch for releasing said connection in response to predetermined circuit opening movement whereby said spring is effective to cause instantaneous reclosure of said contact structure independently of said operating means.
